UNITED STATES PATENT OFFICE.

HENRY A. RUETER, OF BOSTON, AND ERASTUS E. WINKLEY, OF LYNN, MASSACHUSETTS.

MACHINE FOR WASHING TUMBLERS.

1,318,111.

Specification of Letters Patent.

Patented Oct. 7, 1919.

Application filed November 21, 1916. Serial No. 132,550.

To all whom it may concern:

Be it known that we, HENRY A. RUETER and ERASTUS E. WINKLEY, citizens of the United States, residing at Jamaica Plain, 5 Boston, Massachusetts, and Lynn, in the county of Essex and Commonwealth of Massachusetts, have invented certain new and useful Improvements in Machines for Washing Tumblers; and we hereby declare the 10 following to be a full, clear, and exact description of the invention, such as will enable others skilled in the art to which it appertains to make and use the same.

The invention relates to an improvement 15 in machines for washing tumblers and articles of a like nature.

The object of the invention is to produce a washing machine of such construction that the operation of automatically washing or 20 cleaning tumblers and articles of a like nature may be performed more thoroughly and expeditiously than has hitherto been possible with the machines now in use. To the accomplishment of this object, the invention 25 consists in the improved tumbler washing machine hereinafter described and particularly pointed out in the appended claims.

The preferred form of the invention is 30 illustrated in the accompanying drawings, in which Figure 1 is a sectional view taken on the line 1—1 of Fig. 6; Fig. 2 is a sectional detail of one of the valves; Fig. 3 is a sectional view taken on the line 3—3 of Fig. 35 6; Fig. 4 is a sectional view taken on the line 4—4 of Fig. 6; Fig. 5 is a section, on an enlarged scale, taken on the line 5—5 of Fig. 1; Fig. 6 is a top plan of the machine with the cover removed; Fig. 7 is a sectional 40 view taken on the line 7—7 of Fig. 3; Fig. 8 is a partial sectional view, similar to Fig. 1, showing the mechanism of the left-hand part of the machine in a different position; Fig. 9 is a sectional view taken on about 45 the line 9—9 of Fig. 3; Fig. 10 is a section taken on the line 10—10 of Fig. 7; and Fig. 11 is a top plan of the machine on a reduced scale.

The tumbler washing machine illustrated 50 in the drawings consists essentially of two rolls rotating at different speeds, one roll being adapted to support the tumbler during the washing operation and to press it against the other roll—the tumbler being inserted 55 upside down on the first named roll. The difference in the speed of rotation between

the two rolls causes the tumbler to be moved relatively to both rolls, and this movement results in the washing of the sides of the tumbler, means being provided for washing 60 the inside and outside of the bottom. In the machine illustrated in the drawings there are two tumbler supporting rolls, which may be brought into operation separately or simultaneously for pressing two 65 tumblers against the roll for washing the outside of the tumblers. This duplication of the tumbler supporting roll is made merely for the sake of facilitating the washing of a greater number of tumblers, and 70 is not essential to the operation of the machine, one tumbler supporting roll working equally as well as two tumbler supporting rolls in co-operation with the outside washing roll.

The roll for washing the outside of the tumblers is centrally disposed in the machine, and consists of a number of layers of rubber 15, or like material, which are secured to the periphery of a cylindrical 80 core 16 screwed on the upper end of a vertically arranged shaft 17, supported at its bottom end by a boss 18 rising from a web 19 forming a portion of the frame of the machine. Loosely surrounding the lower 85 end of the shaft 17 is a sleeve 21 supported in a lower bearing 22 and in an upper bearing 23. The lower bearing 22 projects upwardly from a web 24, which extends across the whole of the machine and protects the mechanism which actuates the rolls from the water employed for cleaning the tumblers. The upper bearing 23 is connected with the web 24 and with the upper portion 25 of the frame of the machine. 90 Secured to the lower part of the sleeve 21 is a worm gear 26 which meshes with a worm 27 secured to the shaft 28 of a motor 29 supported in a housing 30 located outside the frame of the machine. The motor 100 shaft 28 is journaled in a bearing 32; and a block 33 is interposed between the bearing 32 and the worm 27 for receiving the end thrust of the latter. Formed on the lower end of the sleeve 21 is a pinion 35 which 105 serves to drive a gear 36 secured to a sleeve 37 which loosely embraces a vertically arranged stud 38 fixed in a box-like structure 39 located at the bottom and rear of the machine (Figs. 3 and 7). Secured to the 110 sleeve 37 and situated below the gear 36 is a pinion 40 which meshes with a gear 41

fastened on the lower end of the shaft 17. Below the pinion 40 is a pinion 42 also fastened to the sleeve 37, and which meshes with a gear 43 secured to the upper portion 5 of a cam shaft 44 journaled in the box frame 39. On the shaft 44 are secured an upper ratchet disk 46 and a lower ratchet disk 47, and located above the ratchet disks 46 and 47 are cam disks 48 and 49 respectively, which loosely embrace the shaft 44. By reason of this arrangement, the ratchet disks are normally in constant rotation, while the cam disks remain normally stationary. The purpose and function of these 10 disks will be presently explained. The upper end of the vertically disposed shaft 17 is provided with an oil hole 51, by which the bearing surfaces between the sleeve 21 and the shaft 17, and the bearing surfaces between the sleeve 21 and its bearings, may be lubricated. The lubricant is contained in the cup 52 screwed in the upper end of the shaft 17. A cap 53 closes the upper end of the cylindrical core 16; and an inverted cup-shaped disk 54 serves to prevent water from getting into the bearing surfaces beneath it. The tumbler supporting rolls, which are indicated generally at 56 and 57, are best seen in their relative positions with respect 20 to the central roll in Fig. 1. The right-hand roll is shown in the act of washing a tumbler 58, and the left-hand roll is shown in its normal position, a tumbler 59 having been placed upon it. Each tumbler supporting roll consists of a cylindrical outer portion 60 composed of rubber or like yielding material, which is secured to a cylindrical core 61. The core 61 is fastened to the upper end of a sleeve 62 which loosely embraces, for sliding purposes, the upper end of a shaft 63 journaled in a sleeve 64 which rises from the middle portion of a yoke 65 provided at each end with downwardly depending lugs 66, which are received between 30 upwardly extending bosses 67 rising from the upper surface of the web 24. The upper end of the shaft 63 is provided with a driving head 69, (best seen in Fig. 5), which is adapted to slide in a slot 70 cut in the upper end of the sleeve 62. In this manner provision is made so that the shaft 63 may drive the roll 60, and the roll 60 may be moved longitudinally relatively to the shaft. A helical spring 72 surrounding the shaft 63, the upper end of the spring taking against a shoulder 73 on the sleeve 62, and the lower end of the spring taking against a roller bearing block 74, which is provided to eliminate friction, 40 serves to normally maintain each tumbler supporting roll in the elevated position which the left-hand supporting roll 56 occupies in Fig. 1. Secured to the lower end of each shaft 63 is a gear 76 which meshes 65 with a large pinion 77 secured to the sleeve

21. The gears 76 are in constant engagement with the pinion 77, whether the tumbler supporting rolls occupy their normal position, as shown by the position of the left-hand roll in Fig. 1, or whether they 70 occupy their operative position, as shown by the position of the right-hand roll in Fig. 1. The upper end of each tumbler supporting roll is closed by a cap 75, on the top of which is secured a rubber disk 78 for 75 cleaning the inside of the bottom of the tumbler. It will be observed that by reason of the different sizes of the gears provided for driving the central roll and the tumbler supporting rolls, the two tumbler supporting rolls are driven at one speed and that the central roll is driven at a different speed. The left-hand and right-hand tumbler supporting rolls are respectively provided with push rods 80 and 81. The push rod 80 85 is provided with an upper head 82 and a lower head 83. The push rod 81 is provided with an upper head 84 and a lower head 85. When a tumbler is inserted on each or both of the tumbler supporting rolls, as shown in 90 Fig. 1, the operator presses down upon them until the lower heads of the push rods engage the heads 86 and 87 of the rods 88 and 89 respectively. These rods 88 and 89 are slidingly mounted in vertical holes in bosses 95 at each side of the web 19. When a tumbler supporting roll has been pushed down as far as it will go, it occupies a position as shown by the position of the left-hand tumbler supporting roll in Fig. 8, the head of the push 100 rod then being engaged and temporarily held by a catch 90 pivoted at 91. Each catch 90 is pressed toward its respective rod by means of a spring-pressed plunger 92, the stop 93 limiting the movement thereof. The 105 lower ends of the rods 88 and 89 rest on the outer ends of levers 94 and 95 respectively. Each of these levers is provided with a wedge-shaped structure 96, upon which normally rests the outer end of a dog 97 pivoted 110 to a lug 98 depending one each from the under surfaces of the cam disks 48 and 49. The ratchet disks 46 and 47 are provided with ratchet teeth 100, each of which has a vertical surface and an oblique surface, the 115 vertical surfaces facing in the direction of rotation of the ratchet disks. When a push rod has been moved into the position shown in Fig. 8, the consequent depression of one of the rods 88 or 89 oscillates either of the 120 levers 94 or 95 so as thereby to swing the cam wedge 96 clear of the outer end of the dog 97. Thereupon the dog descends under the action of gravity and is caught by one of the ratchet teeth 100, and the cam disk 125 to which the dog is articulated is rotated synchronously with its respective ratchet disk.

The upper cam disk 48 is provided with an outer cam surface 101 and an inner cam 130

surface 102, and the lower cam disk 49 is provided with an outer cam surface 103 and an inner cam surface 104. The cam surfaces 101 and 103 consist of short segments, 5 and the cam surfaces 102 and 104 comprise complete circles, and are provided with inactive depressed portions 105 and 106 respectively. The lower cam disk 49 is adapted for coöperative action with the left-hand 10 tumbler supporting roll, and the upper cam disk 48 is adapted for coöperative action with the right-hand tumbler supporting roll. The cam surface 103 is normally engaged by a cam roll 108 carried on the outer end 15 of the arm 109 of a bellcrank lever 110 pivoted on a stud 111 secured in the machine frame. The outer end of the other arm 112 of the bellcrank 110 engages the upper side of a pin 113 passed through the lower end 20 of a rod 114 slidingly mounted in an elongated boss 115 depending from the under side of the web 24. To the upper end of the rod 114 is secured an inverted cap 116 pivoted to the outer end of an arm 117 integral 25 with the left-hand tumbler roll supporting yoke 65. A spring 119 tends to raise the rod 114. The construction of the corresponding parts of the right-hand tumbler supporting roll is similar. The outer cam 30 surface 101 of the cam disk 48 normally engages a cam roll 121 carried by the outer end of the arm 122 of a bellcrank lever 123 fulcrumed on the stud 124 secured in the machine frame. The other arm 125 of the 35 bellcrank 123 engages a pin 126 passed through the lower end of a rod 127 slidingly mounted in a boss 128 depending from the web 24. To the upper end of the rod 127 is secured a cap 129 pivoted to the outer end 40 of an arm 130 integral with the right-hand tumbler roll supporting yoke 65. A spring 131 tends to raise the rod 127. When the parts of the machine are in normal or inactive position, the cam surfaces 101 and 103 45 respectively engage the cam rolls 121 and 108, thereby causing the outer ends of their respective levers to depress the rods 114 and 127, against the action of the springs 119 and 131 respectively, so that the tumbler 50 supporting rolls are held in the position of the left-hand tumbler supporting roll as shown in Fig. 1. But when tumblers have been inserted on the tumbler supporting rolls, and they have been pushed down until 55 the rods 88 and 89 have been depressed sufficiently to oscillate the levers 94 and 95, thereby swinging the wedges 96 clear of the dogs 97, whereby the dogs are permitted to be engaged by the ratchet teeth 100 of the 60 ratchet disks, the cam disks are rotated and the cam surfaces 101 and 103 are caused to pass from under the cam rolls 121 and 108 so that the springs 119 and 131 act to throw the tumbler supporting rolls into the position occupied by the right-hand tumbler 65

supporting roll in Fig. 1. This causes the outside of the tumbler to be quite firmly engaged by the central roll, and the inside of the tumbler to be quite firmly engaged by the tumbler supporting roll. The rubber, 70 by reason of its yielding nature, as the rolls rotate at their different rates of speed, scours the surfaces of the tumbler, the slipping action of the tumbler relatively to the two rolls effectively causing the complete 75 circumference of the inside and outside of the tumblers to be engaged and therefore washed before the washing operation ceases. Immediately the tumbler supporting rolls assume their vertical operative position with 80 relation to the central roll, the lower heads 83 and 85 of the push rods 80 and 81 respectively are disengaged from the catches 90, and the springs 132, which are connected with the levers 94 and 95, act to return the 85 levers to their normal position, as shown at the right-hand part of Fig. 1. The wedges 96 are thereby returned to their normal position in the path of the outer ends of the dogs 97. Each wedge is provided 90 with a wall 133 against which the end of the dogs 97 strike. The cam disks are thereby positively stopped at a definite point in their rotation. It is thus seen that during the washing operation of each tumbler, the cam 95 disks perform only one revolution. The washing rolls, however, and perforce the tumblers, are rotated many times during the single revolution of the cam disks.

The rotation of the cam disks causes the 100 depressed portions 105 and 106 of the cam surfaces 102 and 104 respectively to pass from under the cam rolls 135 and 136 (Figs. 7 and 9), by which the cam surfaces 102 and 104 are respectively engaged. The cam 105 roll 136 is carried by a stud secured in an arm 137 of a lever 138 pivoted on a stud 139 secured in the bosses projecting rearwardly from the box frame 39. Upon the free end of the arm 137 rests the lower end 110 of a valve rod 140, the upper end of which is slidingly received in a hole in the web 24. Secured to the upper end of the rod 140 is an inverted cap 141 to prevent water from reaching the lower part of the machine. The upper end of the rod 140 terminates immediately below the lower end of a valve stem 142 of a valve 143. 115

The cam roll 135 is fulcrumed on a stud 144 fixed in an arm 145 of a lever 146 fulcrumed on a stud 147 fixed in bosses situated above the stud 139 at the rear of the box frame 39. Resting upon the outer end of the arm 145 is a valve rod 149, the upper end of which is slidingly received in a 120 hole in the web 24. An inverted cap 150 is secured to the rod 149, and prevents water from leaking down through the space between the rod 149 and its hole in the web 24. The upper end of the rod 149 terminates 125 130

nates below the lower end of a valve stem 152 of a valve 153, the internal construction of which is shown in Fig. 2. The internal construction of the valve 143 is similar in all respects to the valve 153. Each valve stem is provided with a valve disk 154 which is kept normally seated by a spring 155. When the active parts of the cam surfaces 102 and 104 come into engagement with their respective cam rolls, and thereby act to raise the valve rods 149 and 140 so that the upper ends of the valve rods are respectively brought into engagement with the valve stems 152 and 142, the valve disks 154 are unseated, thereby permitting the water held in check to pass into the tubes 157 and 158 respectively. These tubes run toward the front of the machine, and terminate in upright pipes 159 and 160. These pipes direct jets of water on the outside of the tumblers through small apertures 161. Branching from each side of the tubes 157 and 158 are four heads 162, two from each tube respectively. These heads are provided with apertures 163 through which streams of water are squirted into the inside of the tumblers. The valves are joined by a pipe 164 and are supplied by a main 165. When the depressed portions 105 and 106 of the cam surfaces 102 and 104 respectively are again under their respective cam rolls, the valve springs 155 act to close the valves and push the valve rods down, thereby depressing the cam rolls into their respective depressions. These movements take place when the dogs 97 come into engagement with the stops 133 on the wedges 96.

When a tumbler has been inserted on a tumbler supporting roll, and it has been pushed down so that the push rod is caught by the catch 90, to permit the mechanism to come into operation to slap the tumbler up against the side of the central roll, a swinging door is closed over the aperture through which the tumbler supporting roll is reached in order to prevent any water from squirting out of the machine. The top of the machine is provided with a cover 167, and in this cover are cut two apertures 168, each of which is located over a tumbler supporting roll. The aperture above the left-hand tumbler supporting roll is adapted to be closed by the door 169, and the aperture above the right-hand tumbler supporting roll is adapted to be closed by the door 170.

The doors 169 and 170 are respectively pivoted on the studs 171 and 172 fixed in a rib 173. The outer free ends of the doors 60 slide in grooves 174 formed in the inner edges of a shelf 175, projecting inwardly from the frame of the machine. The door 169 is swung into open position by a cam boss 177 (Fig. 7) formed on the peripheral edge of the lower cam disk 49, and for this

purpose the cam boss 177 is adapted to engage a cam roll carried by the outer end of an arm 179 secured to the lower end of a vertically disposed rod 180 which is journaled in the rear part of the frame of the machine. The upper end of the rod 180 passes through the shelf 175, and to it is secured an arm 181, to the outer end of which is pivoted one end of a link 182, the other end of the link 182 being pivoted to an arm 183 which is in fixed relation with the door 169. When the cam boss 177 is disengaged from the roll 178, due to the rotation of the cam disk, the spring 185, acting through the connections between the arm 181 and the door 169, swings the door 169 on its pivot 171 and thereby closes the opening above the left-hand tumbler supporting roll. Upon the completion of one rotation of the cam disk 49, the cam boss 177 again engages the cam roll 178, thereby forcing the arm 179 outwardly, and with it the arm 181. The outward movement of the arm 181 acting upon the arm 183 swings the door 169 into open position, as shown in Fig. 6. The construction of the operating means for the door 170 is similar in all respects to the construction of the operating means for the door 169. The door 170 is normally held in open position by a cam boss 187 formed on the periphery of the cam disk 48. In holding the door 170 open, the cam boss 187 engages the cam roll 188 carried on the outer end of an arm 189 secured to the lower end of a rod 190. The upper end of the rod 190 projects through the shelf 175, and to it is secured an arm 191, on the outer end of which is pivoted one end of a link 192, the other end of the link being pivoted to an arm 193 which has a fixed relation to the door 170. When the cam disk 48 rotates, and thereby disengages the boss 178 from the roll 188, a spring 195 acts to close the door 170. When the cam boss 187 again comes into engagement with the roll 188, the door 170 is swung into open position. On the under side of each door is secured a piece of resilient material, like rubber, which is indicated at 196. This piece 196 is so located that when the doors are shut, it comes into contact with the outside of the bottom of the tumbler and thereby cleans it as the tumbler rotates.

Means are provided for removing the surplus water from the surfaces of the tumbler. These means are brought into action during the tumbler washing operation, and comprise an inside wiper and an outside wiper. There are two inside wipers and two outside wipers. Each inside wiper 197 is pivoted at 199 on the upper end of a lever 200 fulcrumed at 201 on an upright 202 rising from the upper surface of the web 24. The tumbler wiping portion of the wipers is composed of rubber or some other resilient

water-resisting material which is secured to a frame 203. The wipers are pivoted so that they may be self-adjusting to conform to the inside surface of the sides of the 5 tumbler when in active position. When the tumbler supporting rolls are in normal or inactive position, the inner edge of the upper part of the wipers is held in close proximity with the outer surface of the tumbler supporting roll, as shown at the left-hand side 10 of Fig. 1, and also in Fig. 8. This is for the purpose of enabling the operator to easily insert the tumbler over both the tumbler supporting roll and the wiper. When 15 the tumbler is in the position it occupies during the washing operation the tumbler engaging edge 205 of the inside wipers is brought into engagement with the inside of the tumbler, as shown in the right-hand section 20 of Fig. 1. The means for holding the inside wiper against the tumbler supporting roll while the latter is in inoperative position, comprises pins 207 fixed in the sides of the caps 116 and 129. These pins 207 25 engage the inturned lower ends of the levers 200 while the cam surfaces 101 and 103 are in engagement with their respective cam rolls carried by the levers which control the rods 114 and 127, upon the upper ends of 30 which the caps 116 and 129 are fastened. When, owing to the rotation of the cam disks 48 and 49, the cam surfaces 101 and 103 pass beyond their respective cam rolls, and the springs 119 and 131 are thereby 35 permitted to raise the rods 114 and 127, and so the caps 116 and 129; the pins 207 are disengaged from the inturned lower ends of the levers 200, whereupon the coiled spring 208, with which each lever 200 is 40 provided, is permitted to act upon its lever to swing its outer end outwardly into contact with the inner surface of the sides of the tumbler, thereby removing any surplus water therefrom during the washing operation. 45

The outside wipers which remove the surplus water from the outside surfaces of the sides of the tumblers are carried by the doors 169 and 170. These outside wipers 50 210, which are composed of the same material as the inside wipers, are secured to a framework 211 having an upper arm 212 and a lower arm 213 which engage and are held in position by a stud 214 depending 55 from each door. A helical spring 215, surrounding the stud 214, acts to press the wiper toward the tumbler. When a tumbler has been placed upon one of the supporting rolls, and the door has closed, thereby bringing 60 a wiper 210 into engagement with the outside of the walls of the tumbler, the spring 215 acts to hold the wiper in yielding engagement therewith.

As the water is squirted onto the inside and 65 outside of the tumblers during the washing

operation, it falls onto the upper surface of the web 24. This web slants from the center radially downwardly and outwardly toward the outside of the machine, where a trough is formed, as is clearly shown in 70 Figs. 1 and 4. The front part of this trough is slightly lower than the rear, and in each corner thereof is fixed a drain 217 which gives into a drain pipe 218, by which the used water is conveyed away. 75

It has become apparent from the foregoing description that the left-hand and the right-hand tumbler supporting rolls may be used separately or they may be used alternately or simultaneously in conjunction with 80 the central roll, their actuating parts being so constructed as to permit this diversity of operation. As already described, while the parts are in normal or inactive position the doors 169 and 170 are open, and the tumbler 85 supporting rolls are in elevated position, as shown by the left-hand tumbler supporting roll in Fig. 1. The operator then inverts the tumbler to be cleaned and inserts it over the tumbler supporting roll and the inside 90 wiper. The position of the tumbler at the moment of insertion is shown in Fig. 1. The tumbler is then pushed down until the push rod is caught by the catch 90. The position of the parts of the mechanism at this time is 95 shown in Fig. 8. The depression of the push rods results in the oscillation of either the lever 94 or the lever 95, according to whether the left-hand or right-hand tumbler supporting roll is being brought into operation, and when either of these levers has 100 been oscillated, thereby disengaging the wedge 96 from the dog 97, allowing the latter to fall and be engaged by the ratchet teeth 100 of either the ratchet disk 46 or 105 ratchet disk 47, the cam disk 48 or the cam disk 49 is rotated synchronously with its corresponding ratchet disk. The rotation of the cam disk results in the vertical positioning of the tumbler supporting roll into the 110 position occupied by the right-hand tumbler supporting roll, as shown in Fig. 1. While the tumbler supporting roll is coming into its vertical position, the cam boss formed on the outside of the cam disk passes from engagement with its respective cam roll, and the proper door is closed over the aperture in the cover of the machine. Substantially simultaneously with the attainment of the 115 vertical position by the tumbler supporting roll and the closing of the door, the inner cam surface of the cam disk operates to open the valve controlled by it and allow water to be squirted onto the inside and outside of the tumbler. The closing of the doors 120 125 brings the outside wiper into contact with the outside of the walls of the tumbler, and the attainment of its vertical position by the tumbler supporting roll brings the inside wiper into contact with the 130

inside of the walls of the tumbler. When the cam disk has performed one complete rotation, the depression in the inner cam surface of the cam disk is again opposite 5 its respective cam roll, and the spring 155 in the valve acts to seat the valve disk, thereby shutting off the water; the cam boss again comes into engagement with its respective roll, and thereby opens the door to which it 10 is connected, and the outer cam surface of the cam disk again passes under its respective cam roll, thereby depressing either the rod 114 or the rod 127, by which the tumbler supporting roll is returned to its normal 15 oblique position. Thereupon, the catch 90 having previously released the lower head of the push rod when the roll attained its vertical position, the spring 72 acts to raise the roll and the tumbler into the position shown 20 at the left-hand of Fig. 1, so that the operator may readily grasp the tumbler and remove it.

It will be understood that the principle governing the operation of the tumbler 25 washing machine described above may be embodied in other forms and yet be within the scope of the invention as set forth in the following claims.

Having thus described the invention, what 30 is claimed is:—

1. A machine for washing tumblers and the like having, in combination, a vertically arranged, constantly rotating roll, a tumbler supporting roll constantly rotating and normally disposed at an angle to the first roll, 35 means for causing the axis of the tumbler supporting roll to be brought into parallelism with the axis of the first roll, and means for actuating the rolls at different 40 rates of speed.

2. A machine for washing tumblers and the like having, in combination, a roll, a tumbler supporting roll removed from the first roll by a distance greater than the 45 thickness of the sides of a tumbler, means for causing the tumbler supporting roll to be moved toward the first roll until the sides of the tumbler are gripped between the rolls, means for actuating the rolls at different 50 speeds, means brought into engagement with the outside of the bottom of the tumbler when the sides thereof have been gripped between the two rolls, means for directing jets of water into the inside and onto the outside 55 of the tumbler, means for engaging the inside of the tumbler to remove the surplus water therefrom, and means for engaging the outside of the tumbler to remove the surplus water therefrom.

3. A machine for washing tumblers and the like having, in combination, a roll adapted to engage with the outside surface of the sides of a tumbler, a tumbler supporting roll adapted to engage the inside surface 65 of the sides and the bottom of the tumbler,

means for causing the two rolls to grip the sides of the tumbler between them, means for rotating the two rolls at different speeds, means for engaging the outside of the bottom of the tumbler, means for directing jets 70 of water into the inside and onto the outside of the tumbler, and means for removing the surplus water from the inside and from the outside of the tumbler.

4. A machine for washing tumblers and the like having, in combination, a roll adapted to engage the outside of the tumbler, a tumbler supporting roll for co-operation therewith, means for actuating the rolls at different speeds, a receptacle in which the 80 rolls are contained having an aperture above the tumbler supporting roll, and means for moving the tumbler supporting roll toward the other roll, for closing the aperture for directing streams of water into the inside 85 and onto the outside of the tumbler, and for removing the surplus water from the tumbler.

5. A machine for washing tumblers and the like having, in combination, co-operating 90 rolls, one of which is adapted to engage the outside of the tumbler and the other of which is adapted to support the tumbler and engage the inside thereof, means for actuating the rolls at different speeds, a receptacle 95 in which the rolls are contained having an aperture above the tumbler supporting roll, a door for closing the aperture, means for moving the tumbler supporting roll toward the other roll so as thereby to grip the sides 100 of the tumbler between the two, means for closing the door over the aperture, means for directing streams of water onto the inside and onto the outside of the tumbler, means connected with the door for engaging the 105 outside of the bottom of the tumbler, and means for removing the surplus water from the inside and from the outside of the tumbler.

6. A machine for washing tumblers and the like having, in combination, a roll adapted to engage with the outside of the sides of a tumbler, a second roll adapted to support the tumbler in inverted position and to engage with the inside of the sides of the 110 tumbler and with the inside of the bottom thereof, a receptacle for housing the rolls having an aperture, a door for closing the aperture, means connected with the door for engaging the outside of the bottom of the 115 tumbler, means for rotating the rolls at different speeds, means for causing the rolls to grip the sides of the tumbler between them, means for directing streams of water onto the tumbler, and means for removing the 120 surplus water from the tumbler.

7. A machine for washing tumblers and the like having, in combination; a roll adapted to engage with the outside of the sides of a tumbler, arranged vertically in a 130

5 relatively fixed position; a second roll, adapted to support the tumbler in an inverted position and to engage with the inside of the sides of the tumbler, arranged to be moved toward and from the first roll; a 10 spring for supporting the second roll and permitting axial movement thereof; means thrown into operation when the second roll has been moved axially a predetermined distance to move the second roll toward the first to grip the sides of the tumbler between them; and means for rotating the rolls.

15 8. A machine for washing tumblers and the like having, in combination, a tumbler supporting roll adapted to support thereon a tumbler in an inverted position, a second roll adapted to engage the outside of the tumbler, said rolls being normally separated, means for moving the rolls relatively 20 toward each other so as to cause the sides of the tumbler to be gripped between the rolls, means for actuating the rolls at different rates of speed so as to cause the tumbler to be thereby rotated, and means for automatically moving the rolls relatively away from 25 each other.

30 9. A tumbler washing machine having, in combination, a vertically disposed roll rotating in a fixed position, a tumbler supporting roll normally removed from the first named roll, but adapted to be moved toward the latter when a tumbler has been inserted thereover and the roll depressed, means for actuating the rolls at different 35 rates of speed so as to cause the tumbler to be thereby rotated, means for directing jets of water onto the inside and outside of the tumbler, and means brought into engagement with the inside and with the outside 40 surfaces of the sides of the tumbler during its rotation to remove therefrom the surplus water.

45 10. A tumbler washing machine having, in combination, a roll adapted to engage the outside surface of the sides of a tumbler, a tumbler supporting roll normally in an oblique position relatively to the first roll, means for causing the tumbler supporting roll to be moved into parallelism with the 50 first roll so that the sides of a tumbler inserted over the second roll may be engaged between the two rolls, and means for rotating the rolls at different speeds.

55 11. A tumbler washing machine having in combination, a roll having a relatively fixed position, a tumbler supporting roll 60 yieldingly supported in a position above and oblique to the first roll, means thrown into action when a tumbler has been inserted

over the tumbler supporting roll and the latter depressed until its upper end is substantially on a plane with the upper end of the first roll, for moving the tumbler supporting roll toward the first roll so as thereby to engage the sides of the tumbler 65 between the two rolls, and means for actuating the rolls at different speeds.

70 12. A machine for washing tumblers and the like having, in combination, a rotating roll having a relatively fixed position, a tumbler supporting roll having its axis normally displaced with relation to the axis of the first roll, means for yieldingly supporting the second roll, means for actuating the rolls at different rates of speed, a ratchet 75 wheel constantly rotated by the actuating means, a cam disk normally stationary, means for connecting the cam disk with the ratchet disk when the tumbler supporting roll is depressed, and means controlled by 80 the cam disk for moving the tumbler supporting roll toward the first roll until their axes are in parallelism and the sides of the tumbler are gripped between the rolls.

85 13. A tumbler washing machine having, in combination, two coöperating rolls relatively movable with relation to each other, one of which is axially yielding and adapted to support a tumbler in inverted position, means for actuating the rolls at different 90 rates of speed, a water system arranged to direct jets of water onto the inside and outside of the tumbler, an inside wiper and an outside wiper arranged to remove the surplus water from the inside and outside 95 of the tumbler, a receptacle for housing the parts of the machine having an aperture above the tumbler supporting roll, a door for closing the aperture, means connected with the door for engaging the outside of 100 the bottom of the tumbler when the door is closed, a ratchet wheel driven constantly by the roll actuating means, a cam disk normally stationary, means thrown into operation when the tumbler supporting roll is moved axially a predetermined distance for connecting the cam disk with the ratchet disk, means controlled by the cam disk for moving the tumbler supporting roll relatively to the first roll until the sides of the 105 tumbler are gripped between the rolls, means controlled by the cam disk for operating the water system, and means for throwing the wipers into engagement with the tumbler.
